184,141

MIRROR

Harry H. Mook, Memphis, Tenn.

Application January 2, 1958, Serial No. 49,103

Term of patent 14 years

(Cl. D33—9)

FIG. 1.

FIG. 2.

Figure 1 is a front view of the mirror embodying my new design.

Figure 2 is a transverse section taken on the line 2—2 of Figure 1.

I claim:

The ornamental design for a mirror, as shown.

References Cited in the file of this patent

UNITED STATES PATENTS

D. 34,458	Dobbins -----	Apr. 30, 1901
D. 183,141	Padmore -----	July 1, 1958
2,046,595	Yerkes -----	July 7, 1936

OTHER REFERENCES

Montgomery Ward Cat., Fall and Winter, 1952-1953, page 623, items B, E, and J; mirrors.